UNITED STATES PATENT OFFICE.

THOMAS J. ALEXANDER, OF WESTERVILLE, OHIO.

WINDMILL.

SPECIFICATION forming part of Letters Patent No. 378,073, dated February 21, 1888.

Application filed April 30, 1887. Serial No. 236,695. (No model.)

To all whom it may concern:

Be it known that I, THOMAS J. ALEXANDER, of Westerville, in the county of Franklin and State of Ohio, have invented certain new and useful Improvements in Windmills; and I do hereby declare that the following is a full, clear, and exact description thereof, reference being had to the accompanying drawings, and to the letters of reference marked thereon, which form part of this specification, in which—

Figure 1 is a vertical section of a portion of a windmill embodying my invention. Fig. 2 is a plan view of the same. Fig. 3 is a vertical section showing the construction of the brake-strap and lever-connection. Fig. 4 is a plan view of the supporting-ring. Fig. 5 is a similar view of a modified form of ring. Fig. 6 is a detail view showing the lever and brake-strap. Fig. 7 is a detail section showing the connection of the vane-arm. Fig. 8 is a vertical section showing a modification of the spring and controlling devices of the vane. Fig. 9 is a similar view showing a second modification of the same.

This invention relates to improvements in wind wheels or mills, and it has for its objects to provide a mill in which the vane will be held normally in position for keeping the wheel to the wind or in operative position; to allow this vane to yield or turn either right or left independently of the supporting-table when subjected to violent and contrary gusts of wind; to spring-cushion the vane when so displaced, so that shocks caused by sudden stoppage of the vane by impact against other parts of the mill, and consequent liability to damage or breakage, will be obviated; to provide means for throwing the mill out of gear by paralleling the vane and wheel and simultaneously applying a brake to the wheel proper to stop its rotation, and, finally, to automatically return the vane to its operative position after any of its displacements, all of which objects I attain by the present invention, which consists in the novel construction and arrangement of parts hereinafter described, illustrated in the drawings, and particularly specified in the appended claims.

Referring to the drawings by letters, A designates the turn-table or head, which bears the vane and wheel and their controlling mechanism. This head is hollow and of gen-

eral conical shape, having its smaller end lowest.

a designates the depending collared lug or arm by which the head is mounted and allowed to turn freely in suitable bearings on the main supporting-frame of the mill. Near the upper portion of this head, and extending radially and horizontally through suitable bearings formed in the side of the head, is the wheel-shaft B, which bears on its outer end a wind-wheel, *b*, of any suitable construction, and on its inner end a wheel, C, having an eccentric-pin, *c*, for connecting with and imparting movement to the pump rod or pitman, as hereinafter referred to.

D designates an annular horizontal collar or ring secured to the upper edges of head A, or formed integral therewith, as is found convenient. The opening in ring D is of general circular form, but has its center struck from a point outside the center of the ring, so that the periphery of the opening in the ring is eccentric to the periphery of the same.

d designates an offset or notch formed in the opening in ring D at a point where its walls are narrowest, and from which notch the walls widen, as shown and described, forming on the interior surface of the ring the two similar opposite elliptic cams E E, hereinafter referred to. The ring D is situated on head A, so that its notch *d* will be diametrically opposite shaft B, for a reason hereinafter stated.

P designates a hollow pitman-rod rising through the shank *a* of the head A, and suitably connected in the interior of the head with one end of a pitman-rod, F, the other end of which is journaled on the wrist-pin of wheel C, so that when said wheel is rotated by wind-wheel *b* the pitman-rod F will be vertically reciprocated.

G designates a bent arm inside of the head A, the lower end of which encircles a tube through which passes the rod P, on the upper end of which rod is suitably attached the pitman F. The upper tubular portion of the arm G turns cup or step *g*, as shown. This cup can be filled with oil, and when so filled will suffice to lubricate the crane for a year or more, and will, while keeping the lower end of the crane in place, render the movement of the latter easy and frictionless. The upper end of the crane G is supported by a bracket, H,

which is secured at its base to the ring D at a point vertically above shaft B. The bracket H and crane G extend up a sufficient height above the top surface of ring D to allow free swinging movement of the vane I, which is connected by its shaft i with a hollow angular arm, G', formed integral with crane G and extending horizontally outward therefrom, as shown, the arm G' being formed sufficiently 5 near the upper end of the crane to clear the ring D as it swings with the vane I in a horizontal plane, having the crane G as a pivot.

The vane I may be of any desirable construction, but is rigidly connected with crane G, so as to turn and be supported thereby, as described. The lower portion of crane G above rod F is bent outward, so as to offer no obstruction to the vertical play of the rod, and above the limit of vertical movement of the 10 rod the crane is turned inward and rises vertically to bracket H. It is preferably journaled or pivoted to said bracket by having its upper end vertically recessed or dished, so that it can be filled with oil, and into this recess enters a correspondingly-shaped lug on the lower surface of the upper end of the bracket, as shown. Below this recess the portion of crane G vertically above rod F is bored or chambered for the passage of a chain, J, 15 hereinafter referred to, and at the upper end of this bore, just below arm G', is a radial vertical slot communicating with the bore, and in this slot is journaled a pulley, j, over which chain J passes. The crane G is preferably 20 made angular in cross-section for the purpose of affording strength and lightness.

g' designates a lug or arm standing outward from the lower end of crane G in line with arm G' thereof, and to this lug is pivoted the 25 lower end of a rod, K, which extends upward to and through a longitudinal vertical slot, i', in the vane-arm i and arm G' of the crane, the slot i' and rod K both lying within the opening in ring D. The slot i' is provided 30 with a suitable metallic bushing, i'', to prevent wear of the parts.

When in normal position, as shown in Fig. 1, the vane I stands diametrically opposite wheel b and its arm i lies vertically over the 35 notch d in said ring. k designates a friction-wheel turning freely on rod I below arm g and engaging by its periphery against the inner circumference of ring D—that is, the faces of the notch d or cams E E, according as the mill 40 is in operative position or the vane displaced. The wheel k is kept in proper position on rod K by collars, as shown. This wheel may have its periphery grooved, and a corresponding track or guide rail may be formed on the end 45 gaging surfaces of ring D therefor.

k designates a grooved pulley secured between collars on the upper end of rod K, above arm G', and hereinafter referred to.

L designates a spring connected at one end 50 to the crane G and at the other end to the rod K, and which acts to force the rod K away from the crane. This spring is preferably

composed of the double vertical leaves l l, as shown in Fig. 1, the upper ends of the inner leaf l being rigidly secured to the upper portion of crane G below arm G', and secured at its lower end to the lower end of the outer leaf l the upper end of which extends up to and embraces the rod K just below its pulley k, so as to afford the greatest amount of leverage on said rod obtainable. 75

M designates a bell-crank lever pivoted at its bend to ring D above the pulley C, and having one of its arms extending forward and engaging the free end of a brake-strap, d', 80 which is suitably arranged to engage the periphery of wheel C, as shown, so that upon depression of the horizontal arm of lever M the brake d' is forced into contact with wheel C and stops the rotation of the wheel b. The 85 other arm of the lever rises vertically and is connected to the upper end of chain J, which chain passes thence to pulley k', partly around said pulley to pulley j, thence through crane G to and through pitman F, and is passed out 90 of this pitman at a suitable point where it can be manipulated by a person at the base of the frame-work.

The operation of the invention is as follows: The parts being properly mounted and arranged, substantially as described, the vane I stands at right angles to wheel b, in line with the shaft B thereof, and when in this position the friction-wheel k on rod K rests in the notch or recess d in the ring D, this recess 95 corresponding in contour to a greater or less arc of wheel k, so that the vane I, when in said position, will be held with more or less rigidity against swinging movement by means of the springs L, which force outward rod K and 100 keep the wheel k in said notch. The machine is, when thus adjusted, in working position, the wheel b being properly presented and held to the wind, the vane I keeping it properly presented, as usual, by turning head A 105 as the direction of the current of wind varies. Now, should any sudden gust of air come in a contrary direction to that in which the wheel and vane are lying—say, for instance, a gust should strike the vane I at right 110 angles, thereby violently forcing the vane to turn until it stands in line with the current in the usual construction of windmills the shifting of the vane, unless by the mechanisms for throwing the mill out of gear, necessitates the simultaneous shifting of the wheel in an opposite direction, and if the wind is very violent the stability of the mill is endangered, as the wind catches the wheel and vane broadside, and before the vane can right 115 itself the whole mill is blown over. This is especially the case where the independent movement of the vane in one or both directions upon the turn-table is limited by a rigid stop, as, should the wind strike the mill so 120 that the vane would be violently thrown against such stop, the force of the blow would 125 destroy the gravity of the mill-frame and render its overturn by the wind more imminent. 130

By my invention, however, this danger is obviated. No direct stops are employed for the vane; but if such a gust were to strike the mill the force of the movement of the vane 5 would cause wheel *k* to ride out of the notch onto either cam-face *E*, thus increasing the tension of spring *L* on rod *I*, and the farther the vane was displaced the greater tension would be put on spring *L*, as the arrangement 10 of the cams *E* is such that as the wheel *k* rides over them away from notch *d* they direct and force the wheel inward toward crane *G*. This is obvious, as the crane which forms the pivot of the vane is placed centrally of head *A*, 15 while the circle upon which cams *E E* are made is eccentric to the axis of said head. The slot *g'* allows the upper end of rod *K* to move inward as the vane is displaced. When the vane *I* is freed from the air-currents or 20 other disturbing cause, the spring *L*, acting through rod *K* and wheel *k*, will cause the latter to ride down cam *E* until the wheel *k* enters the notch *d*, when the parts are again in ordinary working position.

25 It will be observed that while no sudden stop is given to the vane, yet the farther it is displaced from normal position the greater power is required to cause such displacement, and the greater tension of the spring will cause

30 the speedier return of the vane to its normal position. By reason of this automatic self-regulation of the vane with respect to the wheel the machine can be left set to work at night without fear of its being overthrown.

35 When it is desired to stop the mill or rotation of wheel *b*, the chain *J* is used. By pulling upon the lower end of this chain the brake is applied to wheel *C*, as described, and further pulling or taking up of the chain causes pulley

40 *k* to approach pulley *j*, this causing the disengagement of wheel *k* from its seat, and by still further taking up the chain the vane is swung around until it stands parallel with the perimeter of the wheel *b*, which is then kept

45 edgewise to the wind out of working position, any slight rotative influences of the wind on wheel *b* in this position being rendered ineffectual by reason of the brake on wheel *C*, as described.

50 When the mill is in working position and subjected to a steady and strong current of wind, whereby the rotation of the wheel might be accelerated to a dangerous degree of speed, the vane, being partially independent of the

55 motion of the wheel, as described, will be held in the line of the wind; but the wheel will by its own momentum turn with head *A* until it stands at such a tangent to the wind-current that the full force of the latter is not exerted

60 broadside upon the face of the wheel, and its rotation is consequently lessened. The movement of the wheel and head *A* necessarily causes the friction-wheel *k* to ride up out of its seat upon a cam, *E*, tensioning spring *L*, as is 65 obvious from the fact that vane *I* is held in one position by the wind, or in line therewith. Upon the cessation of the wind the spring *L*

will force the vane back to its normal position and bring the wheel broadside to the wind again.

70 It is obvious from the foregoing that by regulating the tension of spring *L*, I can also in a manner regulate the degree of rotation or speed of the wheel.

75 N, Fig. 1, designates a cap or cover placed over head *A* and secured thereon in suitable manner, so as not to interfere with the working of the vane. The sides of the head may also be closed, if desired, and thus the working parts effectually protected from the weather.

80 Fig. 5 shows a modified form of ring *D*. In this a second recess is made in the interior of the ring opposite notch *d*, for receiving the wheel *C*, as shown, the operative portions of cams *E E* being still preserved.

85 In Fig. 8 I have also shown a modified form of spring *L*. In this the spring is made of a solid bar or rod with one or more coils at its lowest point, and is connected by its opposite ends to the crane *G* and rod *K*, as described.

90 If desired, the wheel *k* could be mounted direct on the outer arm of the spring *L* and the rod *K* dispensed with, the spring-arm taking its place, as shown in Fig. 9; but the described construction is preferable, in that any tension

95 or twisting strain on the spring is avoided. It is also obvious that various modifications in the form and arrangement of springs and arms and the devices for automatically returning the vane to its normal position can be em- 100

ployed without departing from the essential features of my invention, which are the piv- 105

ing of the vane so that it can turn independ- 110

ently of, but upon, the turn-table in any di- 115

rection and keep it normally in proper posi- 120

tion to present the wheel to the wind, and an 125

arrangement of cam-faces and devices acting therewith to return the vane to its normal position after displacement and for spring-cush- 130

ioning the vane when so displaced.

Having described my invention, what I claim is—

1. The combination, with a suitable sup- 115

porting turn-table or head, of an eccentric 120

ring, *D*, having cam-faces *E E* mounted there- 125

on, a vane pivoted by its shaft to a suitable 130

support on said head above the ring *D*, spring- 135

controlled rod *K*, playing through a vertical 140

slot in the vane-arm, and a friction wheel or 145

roller, *k*, on rod *K*, adapted to engage the cam- 150

faces *E E* of the ring to return the vane to nor- 155

mal position after displacement, all substan- 160

tially as described.

2. The combination, in a windmill, of the 165

head *A*, the wind-vane pivoted centrally 170

thereon, the ring *D*, having cam-faces *E E* 175

and recess *d*, with the friction-wheel *k*, mounted 180

on a spring-controlled rod playing through a 185

vertical slot in the vane-arm, and engaging 190

with the cam-faces *E E* to return the vane to 195

its normal position after displacement and 200

with the recess *d* to hold it in such position, 205

all constructed and arranged substantially as 210

and for the purpose described.

3. The combination, with a turn-table bearing a wind-wheel and wind-vane, the latter swinging freely in either direction, of cams mounted on the turn-table, and a spring-controlled friction-pulley engaging with said cams and the vane, whereby the latter is automatically returned to its normal position after displacement, substantially as described.

4. In a windmill, the combination of a support, A, having a tapered tubular neck, a wind-wheel, a crank-wheel having a pitman-rod connected to a tubular rod, P, a bent portion, G, having an upper tubular portion cupped and receiving the lower end of a lubricating device, and also provided with a foot-collar connecting it to the tube which surrounds the rod P, an eccentric ring, D, and a wheel playing therein connected to the pull-chain and also to the part G, all constructed and adapted to operate substantially as described.

5. The combination, with the vane and a

turn-table, of the ring D, having an offset, d, and a wheel, k, spring-actuated and connected to the oscillating part G and to the vane, substantially as described.

6. The combination of the head A, the wind-wheel b, shaft B, wheel C and brake-strap therefor mounted thereon, the crane G, and hollow pitman F, constructed and arranged substantially as described, with the vane I, rod K, wheel k, spring L, cam-ring D, the pulleys j k', crank-lever M, and chain J, all constructed and arranged to operate substantially as and for the purpose described.

In testimony that I claim the foregoing as my own I affix my signature in presence of two witnesses.

THOMAS J. ALEXANDER.
